UNITED STATES PATENT OFFICE.

JOHN B. WINN, OF WATERTOWN, DAKOTA TERRITORY.

LIFTING-JACK.

SPECIFICATION forming part of Letters Patent No. 367,881, dated August 9, 1887.

Application filed February 5, 1887. Serial No. 296,685. (No model.)

To all whom it may concern:

Be it known that I, JOHN B. WINN, a citizen of the United States of America, residing at Watertown, in the county of Codington and Territory of Dakota, have invented 5 certain new and useful Improvements in Lifting-Jacks, of which the following is a specification, reference being had therein to the accompanying drawings.

10 This invention relates to improvements in lifting-jacks; and it consists in the construction and arrangement of the parts, whereby heavy bodies can be raised with ease and rapidity, they can be automatically retained in a raised 15 position, they can be lowered after being so raised without loss of time, and certainty and rapidity of action and lightness and simplicity of construction are attained.

In the drawings, Figure 1 is a side elevation 20 of the invention. Fig. 2 is a plan view of the same. Fig. 3. is a cross-section.

Upon the base A of the machine are rigidly fixed the standards B B'. The said standards are constructed of hollow pipes, and converge 25 to the head-plate C, to which they are rigidly attached. They are braced at about the middle by the plate D. The standards B' are stepped in more than the standards B, to support the strain upon the lever side of the 30 machine.

Upon the base A, directly under the center of the head-plate C, is fixed the guide E. The said guide is a hollow cylinder extending from said base upward through the bracing-plate 35 D, and is held firmly in position by the same. Surrounded by the said guide E is the rod F. The said rod extends from the base A, when resting upon the same, to above the head-plate C, which has a perforation in the center to accommodate it. The said rod is provided with 40 a head, F', upon which the body being raised rests. Surrounding the said rod F are two collars, G and H, which are somewhat larger in diameter than the said rod, to allow of free 45 passage for the said rod when the said collars are in a horizontal position. The collar H is provided at a point upon its periphery with a depending lug, H', which, when the said collar rests upon the plate C, tilts the same, as 50 shown at Fig. 1 of drawings. This tilting of the collar causes the opposite sides of the per-

foration in the said collar to impinge upon the said rod F. The collar G rests upon the top of the guide E, and is provided upon the side with a perforated lug, G'. It is held in position upon the guide E by means of the coil-spring I, which surrounds the said rod F and bears against the said collar G and head-plate C.

The head-plate C is provided with the slotted 60 bracket C', the ends of the wings of which are perforated to receive a bolt. Fitting between the wings of the said bracket, and provided with a corresponding perforation opposite the perforations in the said wings, is a lever, K. 65 The said lever is suspended in the said bracket by a bolt, which is passed through the perforations in the ends of the bracket and in the lever. The lever K is provided with a perforation at the lifting end for the reception of 70 the link L, which connects the said lever with the perforated lug G' of the collar G.

The parts used in this machine are as light as it is possible to make them. The standards B and B' are hollowed so as to resist any vertical strain, and at the same time lighten the 75 construction. They are also so disposed as to distribute the weight upon them all equally.

In the operation the machine is so placed under the object to be raised that the rod F 80 will be in the line of resistance, and with the head F' resting against the said object. The outer end of the lever K is then depressed, raising the inner end. At the beginning of the upward movement of the inner end of said 85 lever the collar G is tilted until it takes a hold upon the rod F. During the remainder of the stroke the rod F and the object resting upon the head F' are raised. As the rod F passes upward, the collar H is raised to a horizontal 90 position and allows the said rod to pass. When the motion ceases, the said collar is immediately tilted by the depending lug H' and takes a frictional hold upon the said rod F. When the lever is at the end of the stroke, the outer 95 end is raised and the inner end depressed, releasing the hold of the collar G upon the rod F. When the hold is thus released, the spring I, which in the upward movement has been contracted, forces the collar G down upon the 100 top of the guide E. During this operation the rod F is held in its last raised position by

the collar II, which is resting upon the projection II'. This operation is repeated until the object being raised is at the altitude desired. If it is now desired to lower the object without loss of time, the depending lug II' is forced around until it is over the slot C' in the head-plate C, when the collar II will drop to a horizontal position and allow the rod F to pass.

10. What I claim is—

In a lifting-jack such as described, the combination of a lifting-rod adapted to move up and down, a guide for said rod, said guide resting upon and perpendicular to the base of the machine and braced to the standards of the same near the top of said guide, a frame for said machine provided with a head-plate, substantially as described, two collars surrounding and having a somewhat larger diameter than the said lifting-rod, whereby when

the said collars are inclined to the said rod they impinge upon the opposite sides thereof, substantially as described, the one of said collars provided with a projection upon its lower face adapted to rest upon said head-plate of the frame and tilt the said collar, and the other of said collars provided with a perforated lug at one point of the periphery, and suitable mechanism for lifting attached thereto, and a spring surrounding the said lifting-rod and having a bearing against the said last collar and the said head-plate, substantially as set forth.

In testimony whereof I affix my signature in presence of two witnesses.

JOHN B. WINN.
